CLAIM

The ornamental design for a panel light, as shown and described.

DESCRIPTION

FIG. 1 is a top, front and right side perspective view of a panel light showing our new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 in FIG. 1.

The even length broken lines depict portions of the panel light that form no part of the claimed design. In addition, the dot-dash broken lines illustrate enlarged portions of the design. None of the broken lines form part of the claimed design.
